UNITED STATES PATENT OFFICE.

THOMAS E. ARMITSTEAD, OF MAZOMANIE, WISCONSIN, ASSIGNOR OF ONE-HALF TO WILLIAM HARVEY MERRITT, OF NEW YORK, N. Y.

PUZZLE.

SPECIFICATION forming part of Letters Patent No. 448,577, dated March 17, 1891.

Application filed July 11, 1889. Serial No. 317,248. (No model.)

To all whom it may concern:

Be it known that I, THOMAS E. ARMITSTEAD, a citizen of the United States, and a resident of Mazomanie, in the county of Dane and State of Wisconsin, have invented a new and useful Improvement in Puzzles, of which the following is a specification.

My invention consists of a number of balls, as marbles, but of any approved material and size, each having a number of flat faces, on which they will rest with some tendency to prevent rolling, but otherwise round, and being numbered or otherwise distinguishably characterized on the respective faces, in combination with a flat board, plaque, or plate of any approved kind adapted to be easily manipulated by the hand for being shaken to roll the balls, and preferably having a marginal guard to prevent the balls from being shaken off the board, and may have a transparent cover to inclose the balls, if desired.

The game or puzzle consists of shaking the plate to roll the balls thereby and turn up the most faces having the highest or any other predetermined numbers or other characters counting the most or reading or indicating any specified text in the game, all as hereinafter fully described, reference being made to the accompanying drawings, in which—

Figures 1 to 4, inclusive, are plan views of my improved puzzle devices, showing the balls in various different positions and with different faces uppermost as in the progress of the game; and Fig. 5 is a transverse section of the device with a transparent cover.

I provide a plain flat plaque *a*, of any approved form, size, and material, and preferably having a marginal guard-rim *b* extending a suitable height above the surface to prevent the balls from rolling off, and also provide therewith two or any greater number of balls *c*, having several flat faces *d*, preferably six, and also preferably so that each face is diametrically opposite another face, said balls being otherwise round, and I number or otherwise differently characterize the faces of each ball, and also preferably color the several balls or some of them differently. In this example two of the balls are

of like color and the other two lighter and darker, respectively. The characters "90" and "9," written on the plaque, explain the nature of the game in this instance, two of the balls having various numbers, or they may be blank on all the faces but one. Each has "9" on one face. Another has "0" on one face and various other characters on the other faces, and one has the character "&" on one face, and is likewise differently numbered or may be blank on the other faces.

The point of the game is to shake the plaque and by that means turn up the reading "90" and "9," as, for example, in Fig. 4. Of course any other reading or count of numbers may be used, and the game may be limited to two balls or increased to any higher number.

As the balls have not to be handled, it is desirable to inclose them for protection against being thrown off and scattered about the floor, and as it is important at the same time to see them plainly I employ in some cases a transparent cover, as *e*, preferably of glass.

The balls of my improved game are distinguished from dice in being round, except in the flattened parts, and they are used by rolling them about through shaking the plaque laterally, whereas dice are cubes, and they are used either by throwing onto the plaque from a cup or by thrusting them upward from the plaque by violent thrusts of the plaque, and while some dice have been made in cubes with the corners slightly rounded, they are yet essentially and practically cubes and incapable of rolling like a ball and are not the equivalent of my balls, which for the purposes of my invention must be capable of rolling and without much tendency to stop even when falling on a flat face. My balls have an essentially distinguishing feature as compared with dice having rounded corners, and that is necessary to my purpose, but not necessary and would be objectionable for dice—viz., the flat faces are of such limited dimensions that they are each entirely bounded by portions of the surface of the sphere.

What I claim, and desire to secure by Letters Patent, is—

1. The improved game or puzzle device comprising the plaque and two or more essentially round balls, each having two or more flat and numbered or otherwise characterized 5 faces, each bounded by portions of the surface of a sphere, in combination, said plaque having the marginal guard for retaining the balls and adapted to be held in and manipulated by the hands to roll the balls thereon 10 to expose the necessary faces to solve the puzzle, substantially as described.
2. The improved game or puzzle device comprising the plaque and two or more essentially round balls, each having two or more 15 flat and numbered or otherwise characterized faces, each bounded by portions of the sur-

face of a sphere, in combination, said plaque having the marginal guard, and the transparent cover for retaining the balls and containing the balls within the marginal guard and adapted to be held in and manipulated by the hands to roll the balls thereon to expose the necessary faces to solve the puzzle, substantially as described.

In testimony that I claim the foregoing as 25 my invention, I have signed my name, in presence of two witnesses, this 1st day of July, 1889.

THOS. E. ARMITSTEAD.
